UNITED STATES PATENT OFFICE.

JOHN H. TALGE AND WILLIAM C. KOSS, OF ST. JOSEPH, MISSOURI;
ASSIGNORS TO ALFRED FRESCHL, OF CHICAGO, ILLINOIS.

TUFTING-MACHINE.

SPECIFICATION forming part of Letters Patent No. 690,206, dated December 31, 1901.

Application filed August 4, 1898. Serial No. 687,759. (No model.)

To all whom it may concern:

Be it known that we, JOHN H. TALGE and WILLIAM C. Koss, citizens of the United States, and residents of St. Joseph, in the county of Buchanan and State of Missouri, have invented a new and useful Tufting-Machine, of which the following is a specification.

Our invention relates to that class of upholstering-machines which are designed to facilitate the manufacture and improve the qualities of tufted cushions or covers for lounges or other upholstered articles; and the objects of our invention are to provide a new and improved machine of this class in which the pins or button-projectors are adapted to be operated in sections, each section being operative independent of the others, and to provide certain improvements in the combinations and arrangements of parts, as hereinafter described and claimed.

With these objects in view the invention consists in certain features of construction and combination of parts, which will be hereinafter fully described and claimed.

In the accompanying drawings, Figure 1 is a transverse section of our invention, cut on line X X of Fig. 2. Fig. 1^a is a perspective view of the socket-wrench. Fig. 2 is a longitudinal section of the machine. Fig. 3 is a top plan of one section of the mold and the staple-guides secured thereto. Fig. 4 is a plan view of one of the various forms in which the mold-sections may be made. Fig. 5 is a side elevation of the same.

Referring to Fig. 1, the base 1, side pieces 2 and 3, (having a channel 4 in their upper faces,) the reinforcing-piece 5, and the two end pieces 6 (only one of which is shown in Fig. 2) constitute a mold constructed in accordance with our invention. To the upper side of the base 1 and in line with the perforations therein is attached a series of suitably-shaped pieces 7; preferably of metal, which form partitions or division-walls for a series of cells or pockets formed in the following manner: When a number of pieces 7 are arranged with their ends 10 against ends 11, as shown in Fig. 1, and sides 12 of pieces 7 are arranged against sides 13 in the same manner as the sides 10 and 11, there is formed

a series of cells or pockets between said pieces 7 with partitions 9. Two suitable guides 14 are pivotally attached to the partitions 9 by rivets 15. The piece 7 is so formed as to provide a tube or hollow guard 16, in which moves a button-projector or pin 17, forced upwardly by the eccentric 18 on the shaft 19, rotated manually by the socket-wrench 20, applied to the square end 21 of said shaft. The pin 60 or projector is retracted by gravity. The eccentric-shafts are suitably supported on brackets 19', secured upon the under face of the mold, and are arranged to be independently operated, whereby the corresponding 65 row of pins may be operated independently of the other rows. To the side pieces 2 is connected a follower-board consisting of slats 22, connected by hinges 23, the free ends of the slats being provided with latches 24, arranged 70 to engage hooks 24^a, attached to side piece 3.

In the operation of our invention we first place buttons 25, with their suitably-attached staples or prongs 26, in the tubes or hollow guards 16, said buttons 25 resting upon the 75 pins or button-projectors 17 and the points of the staples 26 being arranged to project above the staple-guide 14, as shown at point a in Fig. 1. We then spread the fabric or material 27 forming the outer surface of the 80 tufting with its finished ornamented face downward upon the described cells or pockets, after which said fabric 27 is pressed into each and every cell or pocket and over the points of staples 26 by which said fabric 27 85 is held in place, and the thus-formed tufts are rendered permanent by inserting into each and every tuft the requisite amount of stuffing material 28, after which a layer 29 of suitable stuffing material is evenly spread 90 over all the material 28 to a sufficient depth to entirely cover the points of staples 26, after which burlap or other strong backing material 30 is evenly spread over the material 29. The slats 22 are now successively turned 95 on their hinges 23 to a horizontal position from the vertical position indicated by dotted lines in Figs. 1 and 2 and are engaged with the hooks 24^a and hold the burlap pressed downward in place. The materials of the 100 thus-formed tufting are permanently and very substantially secured together in the fol-

- lowing manner: The staples 26 of the buttons are independently forced upward through the fabric 27 by a one-half rotation of the eccentric 18 on the shaft 19, manually rotated by 5 the socket-wrench 20, after which a common metal washer 31 is passed over the points of the staples 26 and said points then clenched, as shown at the left-hand side of Fig. 1. After all the staples are thus clenched the slats 10 22 are unlatched and swung backward to the position shown in dotted lines in Figs. 1 and 2, and the thus-finished tufting is ready for removal and direct attachment to the desired article.
- 15 If desired, we may employ suitable guides, such as are shown at 14, which are pivoted on rivets 15, to be turned in a vertical position by the buttons 25 as said buttons pass upward between them.
- 20 While we have described tubes or hollow guards 16 (shown in Figs. 1 and 2) as being formed integral with the partitions 9, it is evident that they may not be made integral with these partitions, and we therefore reserve to 25 ourselves the right to variously modify the construction and arrangement of these tubes to accommodate the various kinds of work for which the machine is used. For instance, in Figs. 4 and 5 we have shown plain tubes.
- 30 The button used is an ordinary upholsterer's button or tuft-button having a head and the usual prongs or staples constructed in any suitable manner.
- The channels 4 in the side pieces receive 35 the ends of the upper and lower fabrics.
- While we have shown and described the projector 17 as being driven upward by the eccentric 18, it is evident that any other well-known or approved mechanism may be substituted for forcing the projectors to their work, and we therefore do not wish to be restricted to the form of mechanism herein shown and described.
- What we claim is—
- 45 1. In an upholstering apparatus, tuft-button pins arranged in independent sections.
2. In an upholstering apparatus, the combination with a mold, of pins arranged in independent sections, and means whereby the 50 buttons on the pins are forced through the material in the mold.
3. In an upholstering apparatus, the combination of pins arranged in independent sections, and means for operating each section.
- 55 4. In an upholstering apparatus, the combination of a moldboard having hollow guards, a follower-board having openings corresponding to said guards, and pins arranged in independent sections separately operative.
- 60 5. In an upholstering apparatus, the combination with a mold having hollow guards provided with button-guides, a follower-board

having openings to register with said guards, of pins arranged in independent sections, and means to operate said sections independently. 65

6. In a device of the class described, the combination with a stationary supporting frame carrying the projector-tubes thereon, of the follower-board opposed to the tubes and coöperating with the supporting-frame to hold 70 the material in its compressed condition, pins or projectors mounted to slide in said tubes, and eccentric supporting and operating mechanism for said pins whereby they may be forced through the tubes independently of 75 the frame and follower-board.

7. In a device of the class described, the combination with the supporting-frame carrying the projector-tubes thereon, of the follower-board opposed to the tubes and coöperating with the supporting-frame to hold the material in its compressed condition, pins or projectors mounted to slide in said tubes and adapted in their retracted position to support the tufting-buttons within the tubes but with 85 their staple-points projecting just above the tops of the tubes, and means for moving said pins upward to force the buttons through the material and uppermost fabric.

8. In a device of the class described, the combination with the supporting-frame carrying the projector-tubes thereon, of the follower-board opposed to the tubes and coöperating with the supporting-frame to hold the material in its compressed condition, pins or projectors mounted to slide in the tubes and adapted in their retracted positions to support tufting-buttons within the tubes but with their staple-points projecting just above the tops of the tubes, staple-guides pivoted in the 100 upper ends of said tubes within the path of movement of the tufting-buttons, and means for moving said pins upward to force the staples of the buttons through the material and uppermost fabric. 105

9. In a device of the class described, the combination with the stationary supporting-frame carrying the projector-tubes thereon, of the follower-board opposed to the tubes and coöperating with the supporting-frame to hold the material in its compressed condition, pins or projectors mounted to slide in said tubes, and rotatable shafts mounted beneath the tubes and carrying the eccentrics upon which the pins or projectors rest and by which 115 they are forced upward for the purpose described.

In testimony whereof we affix our signatures in presence of two witnesses.
